UNITED STATES PATENT OFFICE.

GUY H. ELMORE, OF SWARTHMORE, AND HORATIO V. CROLL, OF PHILADELPHIA,
PENNSYLVANIA.

JIG-PLUNGER.

1,108,558.

Specification of Letters Patent.

Patented Aug. 25, 1914.

Application filed March 4, 1914. Serial No. 822,367.

To all whom it may concern:

Be it known that we, GUY H. ELMORE, a citizen of the United States, residing at Swarthmore, in the county of Delaware and State of Pennsylvania, and HORATIO V. CROLL, a citizen of the United States, residing at Philadelphia, in the county of Philadelphia and State of Pennsylvania, have invented certain new and useful Improvements in Jig-Plungers, of which the following is a specification.

This invention relates to plungers for jigs, and particularly to an inclosed driving and guiding mechanism for the same.

The purpose of the invention is to secure a simple right line guide for the plunger, protect all the working parts from water and grit, and secure constant and abundant lubrication.

The invention may be applied to any type of plunger, but is particularly adapted to use with so-called valve plungers, and is illustrated as applied to such a plunger. In this type of plunger, the plunger proper is smaller than the plunger compartment and is provided with a flaring elastic valve flap around its periphery. This swings into sealing relation with the walls of the plunger compartment on the down stroke, and swings away from said walls on the upstroke, the plunger proper being so guided as never to touch the walls of the compartment. The best action of such plungers can only be secured by giving them a true and preferably vertical right line movement. The desired result may be secured by the use of the present invention.

Regardless of the particular form of the plunger with which it is used the use of the invention effects a material saving in power and wear on the working parts.

The invention will now be described in connection with the accompanying drawings, in which:

Figure 1 is a vertical section of the device on a plane transverse to the drive shaft; Fig. 2 is a vertical axial section; Fig. 3 is a section on the line 3—3 of Fig. 2, illustrating the guide mechanism in detail; and Figs. 4 and 5 are fragmentary views of a modified form of guide mechanism, Fig. 5 being a section on the line 5—5 of Fig. 4.

In the drawings the plunger compartment 1 of the jig is illustrated as furnished with bronze wear plates 2, mounted therein and

approximately coextensive with the travel of the jig plunger. The shape of the plunger and its compartment is immaterial, a rectangular compartment being illustrated in the drawings. The plunger 3 is somewhat smaller than the compartment and is provided with a flexible downwardly flaring rim or flange 4, which is adapted to bear against the wear plates 2 on the down stroke and swing clear thereof on the upstroke of the plunger. The plunger is guided in the compartment by the guide blocks 24 bolted to its upper face and bearing against the wear plates 2, as shown. In this way the plunger is properly centered in the compartment so that the elastic valve flange will act effectively.

Bolted to the upper side of the plunger 3 is a combined oil case and guide way 5 formed in two parts bolted together at 6, and inclosed at the top by a removable cap plate 7. A removable threaded plug 8 is provided to permit the ready supplying of oil to the interior of the case.

The main shaft 9 of the jig is mounted in suitable bearings 10 and passes through vertically elongated apertures 11 formed in opposite sides of the case 5, the length of the openings being sufficient to permit the desired vertical throw of the jig plunger, and its connected case 5. The apertures 11 are closed and in fact practically sealed in all positions of the device by circular sealing plates 12, fast on the shaft 9, and bearing against the flat sides of the case 5, as shown. Thus the case is free to move vertically with reference to the shaft 9, and yet is closed against the entrance of water and grit.

The case 5 is constrained to vertical rectilinear motion by two guide members each comprising a separable bearing 13 journaled on the shaft 9, together with straight guide bars 14 slidably mounted in vertical ways 15 within the case 5, and preferably formed integral therewith. These bearings may be babbitted as shown. As it is desirable to keep the level of oil contained by the case 5 below the lateral apertures therein, I prefer to use chain oil feeders 16 to assist in lubricating the bearings 13. Other well known forms of conveyor lubricator might be substituted or these might be wholly omitted. The plunger 3 is reciprocated by an adjustable throw eccentric 17, eccentric rod 18 and wrist pin 19 all inclosed by the case 5, as

shown. The use of an adjustable throw eccentric is of course not essential but is desirable in this class of machines. The wrist pin 19 is inserted through the sides of the case 5 and is retained by screw plugs 20, which also prevent any leakage of oil from the case 5. If a sufficiently large eccentric is used it will dip into the oil contained in the case sufficiently to effect its proper lubrication, but in the case of small eccentrics this will not occur unless the oil level is unduly high. Consequently I prefer to add a forwardly extending lubricating tube 23 which is mounted on the side of the eccentric 17 and projects beyond the eccentric strap. This tube is so arranged as to dip into the oil in the case and to conduct the same to the wearing surface of the eccentric.

The guides for case 5 may assume different forms without substantial change of function. For example in Figs. 4 and 5, we show a modified structure in which the case 5 carries guide ways 21, between which slide bearing blocks 22 journaled on shaft 9. In the drawings the blocks 22 are shown constructed in halves to permit easy removal. In Figs. 4 and 5 parts substantially identical with those in other figures are similarly numbered. Other obvious modifications may be made such for example as the substitution of a crank for the eccentric shown and the use of different forms of case. Such modifications are intended to be included within the scope of our claims. We use the expression "crank connections" in the claims to denote generally the mechanical devices of the crank type, capable of converting rotary into positive reciprocating motion. Many such are known and their interchangeability is fully understood.

The use of guide member journaled on the shaft is of importance as it reduces noise and friction and prevents scoring and cutting of the shaft. If the casing were guided merely by the sliding of the shaft in the slots in the case the wear would be unduly rapid and the inherent looseness would cause noisy and otherwise unsatisfactory action.

Having thus described our invention, what we claim is:—

1. In a jig the combination of a plunger casing or compartment; a plunger guided in said compartment; a hollow apertured oil retaining shell rigidly connected to said

plunger; guides within said shell and carried thereby; a rotatable drive shaft passing freely through the apertures in said shell; means for sealing said apertures around said shaft, while permitting motion of said shell transverse to said shaft; a guide member journaled on said shaft and running in the guides on said shell; and crank connections between said shaft and shell and wholly inclosed by the latter.

2. In a jig the combination of a plunger casing or compartment; a plunger guided in said compartment; a hollow apertured oil retaining shell rigidly connected to said plunger; guides within said shell and carried thereby; a rotatable drive shaft passing freely through the apertures in said shell; sealing plates carried by said shaft and adapted to seal said apertures while permitting motion of said shell transverse to said shaft; a separable guide member journaled on said shaft and guided in said guides on said shell; and an eccentric and rod connecting said shaft and shell and wholly inclosed by the latter.

3. In a jig the combination of a plunger casing or compartment; a plunger guided therein; a drive shaft; crank connections between said shaft and plunger; a guide member journaled on said shaft; and an oil retaining casing rigidly connected to the plunger, completely inclosing said crank connections and guided on said guide member to have a reciprocating motion transverse to said shaft and substantially coincident in direction with the motion of the plunger.

4. In a jig the combination of a plunger casing or compartment; a plunger guided therein; a drive shaft; crank connections between said shaft and plunger; a guide member journaled on said shaft; and a complementary guide rigidly mounted on said plunger and adapted to coact with the first named guide member to constrain said plunger to rectilinear motion.

In testimony whereof we have signed our names to this specification each in the presence of two subscribing witnesses.

GUY H. ELMORE.
HORATIO V. CROLL.
